UNITED STATES PATENT OFFICE.

PASCAL J. SHAMPAY, OF CHICAGO, ILLINOIS, ASSIGNOR TO SHAMPAY BROTHERS, OF CHICAGO, ILLINOIS, A CORPORATION OF ILLINOIS.

CLEANING-MACHINE.

1,256,173

Specification of Letters Patent. Patented Feb. 12, 1918.

Application filed January 30, 1913. Serial No. 745,182.

To all whom it may concern:

Be it known that I, PASCAL J. SHAMPAY, a citizen of the United States, residing at Chicago, in the county of Cook and State of Illinois, have invented certain new and useful Improvements in Cleaning-Machines, of which the following is a specification.

My invention relates to scrubbing machines and has for its primary object the provision of an improved scrubbing machine which shall have improved means for scrubbing rugs, carpets, and the like.

With the above and other objects in view this invention consists substantially in the combination, arrangement, and construction of parts, all as hereinafter described, shown in the accompanying drawings, which form a part of this specification and show the preferred embodiment of my invention, and 20 more specifically set forth in the subjoined claims.

In the drawings:

Figure 1 is an end elevation of my invention, with some parts broken away and other 25 parts shown in section.

Fig. 2 is a section taken approximately on the line 2—2 of Fig. 1 and looking in the direction indicated by the arrows.

Fig. 3 is a top plan view of my invention, 30 with the large cylinder shown in Figs. 1 and 2 removed, and with various parts broken away.

Fig. 4 is a detail view, partly in section, of a rug fastener forming part of my invention, with an adjusted position of the 35 parts drawn in dotted lines.

Fig. 5 is a section taken approximately on the line 5—5 of Fig. 4 and looking in the direction indicated by the arrows.

Fig. 6 is a side elevation of a valved feed 40 pipe for liquids forming part of my invention.

Fig. 7 is a section taken approximately on the line 7—7 of Fig. 6 and looking in the 45 direction indicated by the arrows, showing an adjusted position of the parts in dotted lines.

Fig. 8 is an interior view of the feed mechanism shown in Fig. 6, with parts thereof 50 broken away.

Fig. 9 is a section taken approximately on the line 9—9 of Fig. 8 but showing the full circumference of the feed pipe.

Fig. 10 is a view in perspective of a portion of a part shown in Fig. 8. 55

Fig. 11 is a view in perspective of one of a series of scrapers forming a portion of my invention.

Fig. 12 is a section taken on the line 12—12 of Fig. 11 and looking in the direction indicated by the arrows. 60

I secure the soiled rug to the outer periphery of a large cylinder, the warp being next to the cylinder and the nap away from it. The scrubbing and other cleaning devices are disposed adjacent the cylinder and considerably below the horizontal diameter thereof. As the cylinder revolves, it carries the soiled rug downwardly into contact with the cleaning devices in such manner 70 that the nap is scrubbed, leaving the warp so dry that it does not shrink.

Throughout the drawings, reference numeral 20 indicates the main frame of my invention. A rug cylinder 21 is horizontally 75 mounted by means of its axial shaft 22 for rotation in the frame 20. In Fig. 1 is shown the form of mounting preferred by me, wherein the shaft 22 is journaled in the frame on a standard adjustable pillow block 80 indicated generally by the numeral 23. For convenience, this pillow block is mounted upon a hinge 24, which is pivoted on the frame-work at 25. Standard adjustable pillow blocks 23^a, disposed at opposite ends of 85 the cylinder, readily admit of the adjustment of the entire cylinder, while the hinges 24 afford means whereby the cylinder 21 may be swung out of the position shown in Fig. 1 to allow ready access from above to 90 the parts of my invention disposed below the cylinder. At 26 is indicated any convenient fastening means for locking the free ends of the hinges 24 into fixed relation with the frame 20. The arrow indicated by reference numeral 27, in Fig. 1, shows the preferred direction of movement of the cylinder 21. 95

Generally indicated by the reference numeral 28, in Figs. 1, 4 and 5, is an adjustable 100 fastening device for securing the soiled rug to the cylinder 21. This fastening device comprises a longitudinal slot 29 in the cylinder extending from a point adjacent one end thereof to a point adjacent the other 105 end thereof. Two channel irons 30 and 31

are secured in a longitudinal position to the inner periphery of the cylinder 21 and are spaced somewhat apart, the space between them registering with the slot 29. The 5 channel irons are so formed as to include between them an approximately rectangular space 32 extending longitudinally of the cylinder and of about the length of the slot 29. Disposed within the space 32 is a 10 long bar 33 preferably of a semi-rigid material, such as wood. The bar 33 extends the length of the space 32 and is of such size as to be movable within the space 32 preferably along the line of the radius of the 15 cylinder passing through it. Secured along the outer surface of the bar 33, and directly opposite the slot 29, is a rod 34 of compressible material, preferably rubber, extending the length of the bar 33. Pivoted to lugs 20 35 and 36, formed upon the channel irons 30 and 31, are a plurality of oscillating cams 37, shown in Figs. 4 and 5, the pivoting means being a small bolt 38 passing through both lugs and an aperture in the cam. The 25 cams 37 are so disposed with respect to the bar 33 that when oscillated simultaneously they will move the bar in the space 32 toward or away from the slot 29. These cams 37 are disposed at convenient distances along 30 the length of the bar 33 and are actuated simultaneously by a longitudinally reciprocating strip 39, to which each of them is pivoted. For the purpose of obtaining considerable leverage upon the cams 37, each of 35 them bears an arm or extension 40 slotted at its extremity farthest from the pivot 38. Studs 41 protruding from the sides of the strip 39 pass through the slots in the extremities of the arms 40 and form thus a 40 driving connection between the cams 37 and the strip 39. The strip 39 may be reciprocated in any convenient manner, the preferred method being shown in Fig. 4, wherein an angle iron 42 is secured to the channel irons 30 and 31, and is in threaded engagement with a handled shaft 43, which is swiveled in any convenient manner to one end of the strip 39. The rug to be fastened is generally indicated (in Fig. 1) by the reference numeral 44, its warp side being numbered 45 and its nap side 46. In the operation of the fastener 28, one end of the rug to be cleaned is inserted through the slot 29 into the space 32. The handled shaft 43 50 is operated to create a tension upon the strip 39 and thus draw the cams 37 into the position shown in dotted lines in Figs. 4 and 5, for the purpose of forcing the bar 33 and the rod 34 outwardly to cause the rod 34 to 55 pinch the inserted end of the rug 44 against the cylinder 21. In addition to pinching the rug 44 and holding it in its inserted position in the slot 29, the compressible rod 34 completely closes the space 29, making a 60 65 water-tight joint therewith. The rug 44 is

thus fastened to the cylinder in such position that, when the cylinder revolves in the direction indicated by the arrow 27, the nap of the rug will lie exposed upon the outer side of the cylinder 21, and the warp of the rug will lie against the outer periphery of the cylinder. 70

Supported in any suitable manner upon the frame 20 are two guide rollers 47 and 48 serving as guides for the rug 44 as it is 75 drawn onto the cylinder by the revolution of the cylinder in the direction of the arrow 27. For convenience in temporarily holding the end of the rug to be fastened near the cylinder 21 (see Figs. 1 and 3) is provided 80 a series of needle points 49 projecting toward the cylinder and secured to an angle bar 50, which finds its support in any suitable manner upon the frame 20. When a large rug is to be secured to the cylinder, it 85 is drawn up over the needles 49 and pressed down upon them, thus holding it in position adjacent the cylinder 21 while the extreme end of the rug is inserted through the slot 29. The revolution of the cylinder 21 in the 90 direction of the arrow will, without damage to the rug, draw it off the needle points 49. As a protection to the operator from the sharp points of the needles 49, I preferably provide flat springs 51, slotted as at 52 and 95 secured to the angle iron 50 in such position that they may be pressed down at their free ends, causing their slotted portions to descend about the needles 49 and expose the needles for insertion in the rug. When the 100 rug has been drawn off the needles 49, each of the springs 51 rises from its position about the needle and assumes a position above the needle, thereby interposing between the hand of the operator and the 105 point of the needle a protecting body.

As the rug, secured in the fastener 28, is carried on the cylinder in the direction indicated by the arrow 27, it passes over the roller 48 and approaches a valved feed pipe 110 53 disposed below the cylinder, and which is supplied from any convenient source with liquid soap, or other desired liquid cleaning compound. The feed pipe 53 extends longitudinally of the cylinder 21 from a point 115 adjacent one end thereof to a point adjacent the opposite end thereof, and is provided with a plurality of valved openings 54 (see Fig. 8). The valves governing the feed of liquid soap from the feed pipe 53 are shown 120 in Figs. 1, 3, 6 and 7. In the construction of these valves, lugs 55 are provided on the outer side of the feed pipe 53 and protruding laterally therefrom. To each lug 55 is pivoted, intermediate its extremities, a 125 curved valve lever 56, one end of which is provided with a closure 57 for the aperture 54, and the opposite end of which carries a rotatably mounted roller 58. A compression spring member of any suitable form is 130

interposed preferably between the feed pipe 53 and the roller end of the lever 56, holding the closure 57 normally against the aperture 54 to seal the aperture. The rollers 58 are disposed very close to the outer periphery of the cylinder 21, the proximity being such that the thickness of the rug, as it passes between the cylinder 21 and the roller 58, oscillates the lever 56 upon its pivot, thereby 10 opening the aperture 54 and allowing liquid soap to pass outward from the feed pipe 59. This open position of the valved apertures 54 is best shown by the dotted lines in Fig. 7. The cylinder 21 is of such a length that 15 rugs of considerable width can be carried thereon, but it is an advantage of my valved feed pipe that when a narrow rug is to be scrubbed, only those valved apertures 54 which are opposite the rug will be opened 20 by the passage of the rug upon the cylinder, the remaining valved apertures standing closed, thus preventing waste of the liquid soap or other cleaning compound. However, should a rug as wide as the full length 25 of the cylinder be inserted in my machine, all the valved apertures 54 would be opened thereby, thus supplying liquid soap sufficient for the entire surface of the rug. Inasmuch as the action of the levers 56 and 30 closures 57 is non-adjustable, and the oscillating of the levers 56 opens the apertures 54 to their full extent, I provide adjustable means for limiting the passage of liquid through the apertures 54 by furnishing a 35 curved strip 60, preferably of metal, disposed within the feed pipe 53 and adapted to be adjusted within the pipe to partially close, or fully close, if desired, the apertures 54. The strip 60 is given a curve conforming to the inner periphery of the pipe 53 40 and is provided with oblique slots 61, which are engaged by studs 62 protruding from the inner surface of the feed pipe. Draw wires 63, secured to either end of the strip 45 60 and passing out of the feed pipe 53 through small apertures provided therefor, are the means I preferably employ for shifting the strip 60 upon the studs 62. Any other convenient means may, however, 50 be employed. The shifting of the strip 60 causes one edge of the strip to overlap the apertures 54 obstructing the passage of liquid therethrough as much as desired. By thus obstructing the apertures 54, the quantity of liquid emitted from the feed pipe 53 55 may be properly regulated. The supply of liquid soap, or other cleaning compound, is brought to the feed pipe 53, preferably from its end 53^a (see Fig. 3) under sufficient head 60 to cause it to flow freely through the apertures 54, the opposite end of the feed pipe being closed by a plug 64 which is apertured for the passage of the draw wire 63, if such draw wire be used. The draw wire 63 fits 65 the aperture in the plug 64 so closely as to

prevent the leakage of liquid through the plug.

Three cylindrical rotating brushes 65, 66 and 67 are disposed below the cylinder 21 and in such proximity thereto that, when 70 rotated, they will scrub the nap 46 of the rug 44 as the rug, borne by the cylinder, is carried past them. The brushes preferably rotate in the directions indicated by the arrows 65^a, 66^a and 67^a. Chambered inclusions 75 68 and 69 are provided for the brushes for the purpose of collecting liquids thrown from the brushes by centrifugal force. The chamber 69, which incloses the brush 67, is preferably provided with a drain cock 70. 80 As the valved apertures 54 in the feed pipe 53 are opened by the passing of the rug 44, the soap which is emitted from the feed pipe drops from a drip board 71, which is given a slight pitch downward from the feed pipe 85 to a point where the soap will drop off onto the brush 65. The rotation of the brush 65 carries the liquid soap thus dropped upon it up to the nap 46 of the passing rug, wetting the nap of the rug and simultaneously scrubbing 90 it in the direction indicated by the arrow 65^a. In the further passage of the rug, it encounters the brush 66 rotating in an opposite direction, as indicated by the arrow 66^a. Thus it will be seen that in passing 95 the two scrub brushes 65 and 66 the nap 46 of the rug has been scrubbed in each direction. The bottom of the chamber 68 is in close proximity to the brushes 65 and 66, and is given a slight pitch corresponding to 100 the difference in level of the axes of these brushes, from which it will be seen that whatever liquid soap is thrown from the brush 65 will drain down toward the brush 66 and be carried thereby up to the nap 46 105 of the rug. In this way the brush 66 receives its supply of liquid soap. After the soap scrubbing given to the rug by the brushes 65 and 66, it is desirable to scrape from the rug as much as possible of the 110 liquid soap which adheres thereto. For this purpose I provide a double set of soap scrapers 72 and 73, held in contact with the rug by being secured to an angle iron 74, shown 115 in Figs. 1, 3, 11 and 12. These scrapers are preferably formed of a tempered metal, such as steel or brass, and are disposed preferably in parallel lines, the lines being spaced from each other, and the blades being spaced from each other in the lines. This 120 spacing provides for rapid draining of the dirty liquid soap scraped from the rug, the liquid dropping into the chamber 69 and passing out, at the will of the operator, through the drain cock 70. The angle iron 125 74 is secured in position in any suitable manner, preferably by attachment to the frame 20, the precise means, however, not being here shown. Any suitable means, such as bolts 75, may be employed to secure the 130

blades 73 to the angle iron 74, and the spacing of the lines of scrapers from each other may be accomplished in any desired manner, such, for instance, as the employment of 5 collars 76 and bolts 77 somewhat longer than the bolts 75. To permit a firm seating of the collars 76 against the angle iron 74, I partially cut away the lower corners of the blades 73, as at 78 in Fig. 11. For adjustment of the scrapers 72 and 73 toward or away from the cylinder 21, I provide slots 79 for the passage of the bolts 75 and 77. Obviously, by a loosening of the bolts, the blades may be raised or lowered, and the 10 bolts again tightened against them.

The next part of my mechanism acting upon the rug as it travels along on the cylinder 21 is a water pipe 80, shown in Figs. 1 and 3, having a plurality of apertures 81. 15 The water pipe 80 is disposed any suitable distance from the cylinder 21, lies preferably parallel thereto, and the apertured portion thereof extends approximately the length of the cylinder. It is adapted to receive water under a suitable pressure, preferably from its end 82, and the apertures 81 are so disposed as to project the water from the pipe 80 against the nap 46 of the rug 44. Control of the pressure and the amount 20 of water in the pipe may be provided for in any convenient manner, the exact method not being here shown. The pipe 80 is preferably disposed between the scrapers 73 and the brush 67. As the rug passes from a 25 position opposite the water pipe 80, it is scrubbed by the brush 67 by a backward motion, as indicated by the arrow 67^a, the water thrown off by the brush 67 draining downwardly into the lower portion of the 30 chamber 69 and being drawn off, at the will of the operator, through the drain cock 70. After being scrubbed by the brush 67, the rug, in its passage upon the cylinder, is scraped by another double set of scrapers 35 83 and 84, similar to the scrapers 72 and 73, and similarly disposed with relation to each other. This double set of scrapers is preferably secured to an upwardly extending portion of the side of the chamber 69, and 40 sufficient room is allowed beneath the scrapers 83 and 84 for drainage of water scraped from the rug. Secured parallel to the line of scrapers 84, and just outside of it, is a yielding wiper 85 of rubber or similar 45 material, having contact with the surface of the cylinder 21, except where the rug covers the cylinder. This yielding wiper 85 removes the liquids from the cylinder, keeping the surface thereof dry for contact with the 50 warp side of the rug.

In order that the rug, in its passage on the cylinder, may not be buckled or doubled upon the cylinder by the action of the brush 65, which, as indicated by the arrow 65^a, 55 travels in a forward direction against the

rug, I provide, preferably, a series of stiff wire holders 86, shown in Figs. 1 and 3, which serve to hold the rug in contact with the cylinder, and about which the bristles of the brush 65 readily pass.

The liquid soap and the water thrown against the rug in its travel upon the cylinder have, in practice, a tendency to creep away from the rug toward the extreme ends of the cylinder and to drop therefrom, wetting the floor and parts of my machine disposed beneath the ends of the cylinder. To prevent this creeping of the liquids off the extreme ends of the cylinder, I provide peripheral flanges 87 near the ends of the cylinder 21. These flanges, in the lower semi-circle of their travel, pass through channels 88, provided preferably in the ends of the chambers 68 and 69, though the channels may be formed in any suitable member desired having attachment to the frame 20, or in any other suitable manner supported. The channels 88 are provided with apertures 88^a, whereby the liquid collected in the channels may drain downwardly into the chambers 68 and 69. As a further protection against the dripping of liquid from the ends of the cylinder, I provide two strips of a packing material 89, such as thick felt, which press closely against the lower half 95 of the cylinder 21. The strips 89 are seated in channels 90, provided either in the ends of the chambers 68 and 69 or in any other convenient member found desirable, and they are maintained in contact with the lower portion of the cylinder by flat springs 91, which are secured to the bed of the channel 90 and press upwardly against the strips 89.

Power is applied to my rug scrubbing machine in any desired manner, the exact method of application not being here shown. In practice, it is desirable to have the cylinder 21 travel at a peripheral speed of six feet per minute and to have the brushes 65, 105 66 and 67 rotate from 200 to 400 revolutions per minute, though, of course, I do not limit myself in any way to these speeds. In the operation of my machine, a rug or carpet to be scrubbed is brought with its end toward the machine, the end is raised, and the weight of the rug held off of the floor by the insertion along its width of the needles 49. The extreme end of the rug is then inserted through the slot 29 into the space 32, 110 the slot 29 being preferably in a position adjacent but slightly above the roller 48. The handled shaft 43 is then rotated to actuate the cams 37 and press the rod 34 against the end of the rug and the cylinder 21, thus filling up completely the slot 29 and sealing it against the passage of liquid. In this manner, liquid is prevented from entering the interior of the cylinder through the slot 29 when the slot passes over the brushes 65. 115 120 125

66 and 67 and the water pipe 80. The rug is so secured to the cylinder 21 that its nap is exposed to the action of the brushes and the scrapers heretofore described, while its 5 warp lies against the outer periphery of the cylinder. Power is now applied to the machine, and the cylinder 21 begins to revolve in the direction indicated by the arrow 27 (see Fig. 1). As the rug passes the feed 10 pipe 53, the rollers 58 ride up upon its nap, thus opening the apertures 54 in the pipe 53, allowing soap to flow down the drip board 71 to the rapidly revolving brush 65. As the rug proceeds, it passes between the 15 wires 86 and the cylinder, and is violently scrubbed by the brush 65, the soap from the feed pipe 53 being thrown against the nap of the rug by the rapidly whirling brush. The rug then passes onward to the brush 20 66, which scrubs the nap in an opposite direction to that of the brush 65. The brush 66 also applies more liquid soap to the nap of the rug, having received a supply of soap from the lower portion of the chamber 68. 25 Proceeding farther, the rug is scraped by the double set of scrapers 72 and 73, which, being constructed of a tempered metal, bend sufficiently to avoid scraping the nap of the rug from the warp but, nevertheless, press 30 sufficiently hard upon the nap to wipe therefrom most of the liquid soap which has been applied. The head of water is now turned into the water pipe 80, and jets of water are projected against the rug throughout its 35 width from the apertures 81 of the water pipe, thus rinsing the nap of the rug and washing away still more of the soap which has been applied. The nap of the rug now being wet with water, it is necessary to remove 40 as much as possible of the water, and to accomplish this the rug encounters the brush 67, which, rotating in the direction indicated by the arrow 67^a, dashes from the rug all the loose water held by the nap. The double 45 set of scrapers 83 and 84 now press upon the rug for the purpose of pressing out as much as possible of the water still retained by the nap. The yielding scraper 85 readily bends to allow the passage of the rug and wipes 50 a slight amount of water therefrom. However, the scraper 85 is provided rather to perform the function of wiping dry the outer surface of the cylinder than for the purpose of further drying the rug after it 55 has been scraped. The scraper 85 thus keeps the outer surface of the cylinder dry at all times for the instant application of a rug.

From the foregoing description, it is obvious that no liquid is applied to the warp 60 of the rug, thus preventing that shrinkage of the rug which takes place in the ordinary scrubbing process.

In the accompanying drawings, and in the foregoing description, are set forth the preferred embodiment of my invention, but it

is obvious that any one skilled in the art may make modifications of the same without departing from the principle of the invention.

I claim:

1. In a cleaning machine for carpets and the like, the combination of a carrier for a carpet to be cleaned, a feed pipe for liquid cleaning material positioned adjacent the carrier and having a plurality of apertures, and 70 separate valves for the apertures of the feed pipe comprising levers pivoted intermediate their extremities, a puppet upon one end of each lever for contact with the outer side of the pipe and closing the adjacent aperture 80 thereof, the opposite end of each of said levers being spaced from the carrier a distance less than the thickness of a carpet so that the levers will be moved to open the valves when the carpet to be cleaned passes 85 said opposite ends of the levers.

2. In a cleaning machine for carpets and the like, the combination of a carrier for a carpet to be cleaned, cleaning appliances, a 90 normally closed source of supply of liquid cleaning material for the cleaning appliances, and valves controlling the delivery of cleaning material to the appliances, said valves each having a lever with one end spaced from the carrier a distance less than 95 the thickness of the carpet so that the valves will be opened and held open by the carpet being carried as it is moved past the valves.

3. In a carpet cleaning machine, the combination of a carrier for a carpet to be 100 cleaned, cleaning appliances, a normally closed, multiple valved source of supply of liquid adjacent the carrier for feeding cleaning material to the appliances, and opening means for the valves lying in the path of 105 travel of the carpet and actuated thereby.

4. In a carpet cleaning machine, a movable member for carrying a carpet to be cleaned, appliances disposed adjacent the member for cleansing with liquid the outer 110 side of the carpet, and a device for wiping liquid from the carpet and from the surface of the said member after the carpet and member pass the said appliances.

5. In a carpet cleaning machine, a movable member for carrying a carpet to be cleaned, appliances disposed adjacent the member for cleansing with liquid the outer side of the carpet, and a device for wiping liquid from the carpet and from the surface 120 of the said member after the carpet and member pass the said appliances, said device comprising a flexible wiper which is of sufficient resilience to engage both the surface of the member and a carpet thereon for 125 removing superfluous liquid therefrom.

6. A supporting frame, a carrier for carrying an article to be cleaned, rotary appliances disposed below the carrier for scrubbing the lower side of the article, mechanism 130

for securing one end of the article to the carrier, and devices for maintaining the free end of the article in contact with the carrier comprising springs mounted on the frame and so disposed as to bind the article between themselves and the carrier.

7. In a carpet cleaning machine, the combination with a carpet carrying drum of a feed pipe for cleaning material, having a row of discharge apertures in alinement with each other, carpet cleaning appliances adjacent the feed pipe valves controlling the apertures, a controlling arm upon each valve, the free ends of the arms being disposed in alinement, the drum having its carrying surface parallel to the free ends of the arms and spaced from the free ends of the arms a lesser distance than the thickness of the carpet to be cleaned.
8. In a cleaning machine, the combination of a straight feed pipe for cleaning material, having a straight line of discharge apertures, an independent valve for each of said apertures, a controlling arm for each of said valves, the free ends of said arms being in alinement, and a rotatable cylinder adapted to carry upon its surface an article to be cleaned, rotating about an axis parallel to the line of the free ends of the controlling arms, and having its carrying surface spaced from the ends of said arms a distance less than the thickness of the article to be cleaned.

9. In a cleaning machine, the combination of a straight feed pipe for cleaning material having a straight line of discharge apertures, an independent valve for each of said apertures, a controlling arm for each of said valves, the free ends of said arms being in alinement, and a rotatable cylinder adapted to carry upon its surface a rug to be cleaned, rotating about an axis parallel to the line of the free ends of the controlling arms, and having its carrying surface spaced from the ends of said arms a distance less than the thickness of the rug to be cleaned.

10. In a carpet cleaning machine, a movable carrier for supporting a carpet to be cleaned, appliances disposed below the car-

rier for cleaning with liquid the lower side of the carpet, and a device for wiping liquid both from the surface of the carrier and from the cleaned surface of the carpet after the carrier and the carpet pass the appliances for cleaning the carpet.

11. In a carpet cleaning machine, a fluid scrubber, a drum to move the carpet to be cleaned through the scrubber, and means to vary the distance of the drum from the scrubber.

12. In a carpet cleaning machine, the combination with a drum for moving the carpet, of a rinsing brush directly operable upon the carpet, and scrapers to engage the carpet both before and after the carpet is operated upon by the rinsing brush.

13. In a carpet cleaning machine, the combination of a rotatable drum to support and move the carpet, and means for scraping the carpet comprising metal spring pressed scrapers adapted to contact with the carpet as it is drawn past the scrapers by the drum.

14. In a cleaning machine, the combination with a receptacle, of scrubbing brushes rotatable therein, means to draw the article to be cleaned against the said brushes, and a wiper secured to the rear of the receptacle adapted to engage an article to be cleaned and to prevent the cleaning fluid from escaping from the receptacle.

15. In a cleaning machine of the class described, the combination with a fluid receptacle high at the front end, scrubbing means in said receptacle, and a wiper at the rear end thereof adapted to contact with the article cleaned after it has been engaged by the scrubbing means to prevent the escape of fluid from the receptacle and to return fluid from the article cleaned into the receptacle.

In testimony whereof I have signed my name to this specification, in the presence of two subscribing witnesses, on this 27th day of January A. D. 1913.

PASCAL J. SHAMPAY.
